Patented Aug. 30, 1921.

UNITED STATES PATENT OFFICE.

EDWIN N. LIGHTFOOT, OF NEW YORK, N. Y., ASSIGNOR TO THE CUTLER-HAMMER MFG. CO., OF MILWAUKEE, WISCONSIN, A CORPORATION OF WISCONSIN.

ELECTRIC HEATER.

1,389,312.

Specification of Letters Patent. Patented Aug. 30, 1921.

Application filed March 3, 1920. Serial No. 362,991.

To all whom it may concern:

Be it known that I, EDWIN N. LIGHTFOOT, a citizen of the United States, residing at New York, in the county of Bronx and State 5 of New York, have invented new and useful Improvements in Electric Heaters, of which the following is a specification.

This invention relates to an electric heater.

10 More particularly it relates to a flat electric heater having a resistor mounted within but insulated from a sheet metal casing.

An object of this invention is to provide an improved electric heater which may be 15 employed as either a space or surface heater.

Another object is to provide an improved electric heater wherein connection with the resistor thereof is facilitated.

20 Another object is to provide terminals for electric heater which will permit of the mounting of the heater against a flat conducting base with the terminals insulated therefrom or the mounting of several heaters 25 upon conducting bars extending through the terminals of the several heaters.

Other objects and advantages will appear from the following specification and claims.

An embodiment of this invention is illustrated in the accompanying drawings in which:

Figure 1 is a perspective of a heater equipped with a terminal positioned in and insulated from one reinforcing plate thereof 35 and opposite an aperture in the other plate.

Fig. 2 is a sectional view through the terminal.

Fig. 3 is a bottom plan of a heater with parts broken away to show construction.

40 Fig. 4 is a perspective of several heaters mounted upon conducting bars extending through the terminals thereof.

Fig. 5 is a view of the conducting bar with the terminals of two heaters connected therewith, one terminal being in section.

The electric heater illustrated comprises a bottom reinforcing plate 10 having flanges 11 and 12 which may be bent over a top reinforcing plate 13 to form an inclosure for a 50 resistor 14. This resistor is in the form of a flat resistance ribbon wound upon insula-

tion 15 and is separated from the plates by insulating strips 16 and 17.

The plates 10 and 13 are provided with apertures 20 and 21 positioned opposite each other. The insulating strip 16 extends over the aperture 21 to form a window therefor.

A hollow terminal rivet 22 extends through the aperture 21 and aperture 23 in the insulating strip 17. The rivet also extends 60 through an aperture in mounting strip 24 connected with one end of the resistor 14. The periphery of the aperture 21 is struck up to provide a greater separation between the hollow terminal rivet 22 and the reinforcing 65 plate 13. Further insulation in the form of insulating washers 25 and 27 are provided. The ends of the hollow terminal rivet 22 are expanded to clamp the various parts together. A metal washer 26 is provided between the terminal strip 24 and the expanded end of the rivet 22 to provide a bearing 70 surface for the rivet. If desired, a terminal having a perforated base 30 and a perforated extension 31 may be provided and clamped 75 in position with the other parts by means of the hollow terminal rivet 22. This terminal permits of the connection of an electric conductor to the terminal by looping the end of the conductor through the aperture in the 80 projection 31.

Apertures 8 and 9 provided in the ends of the plate 13 extending beyond the ends of the plate 10 are for use when the heater is to be mounted flat against a supporting base. 85 A heater provided with the form of terminal shown may be mounted flat against a base of conducting material and secured thereto by means of screws or bolts extending through the apertures 8 and 9. With the heater 90 mounted in this position the plate 10 thereof is in contact with the conducting base. The terminal rivet 22 is, however, insulated from the base due to the window formed by the insulated strip 16 which extends over the 95 aperture 20. An electric conductor may be connected to the terminal rivet 22 or to the extension 31 of the angular terminal if the latter is provided.

Fig. 4 shows several heaters equipped with 100 the above described form of terminal and mounted upon conducting bars 35 and 36

which extend through the hollow terminal rivets 22. When the heaters are mounted in this manner a hole must be punched in the insulating strip forming the window for the aperture 20. It is obvious that when a hole is punched in this window the heaters may be readily mounted upon the conducting bars 35 and 36. It may be desirable to arrange the heaters upon these conducting bars very close together. If the projecting terminals 31 are in the way when the several heaters are mounted close together upon the conducting bars 35 and 36 each may be easily broken off at the point at which they are attached to the perforated base 30.

Fig. 5 shows one of the conducting rods which is threaded to accommodate a nut 37 upon each side of the terminal rivet 22 to clamp this rivet into good electrical contact with the conducting rod. These nuts 37 also serve to position the heaters upon the rods.

Heaters provided with the above described form of terminal may be mounted in either 25 of the two positions as described.

Electric heaters have been provided which might be mounted against a flat conducting base with the terminal of the heater insulated from the armor thereof and from the conducting base. Electric heaters having terminals through which conducting rods may extend for mounting the heaters thereon have also been provided. The present heater, however, has a decided advantage thereover for it 35 may be mounted in either position. Therefore it is necessary to stock but one type of heater where before it was necessary to carry in stock two types.

The invention contained herein is of course 40 susceptible of other embodiments and adaptations.

What I claim is:

1. An electric heater having in combination a resistor, an insulating strip on each 45 side of the resistor, one of the strips being provided with an aperture, a pair of sheet metal plates forming an inclosure for the insulated resistor and having alined apertures opposite the aperture in the insulating strip, and a hollow terminal rivet connected with the resistor and extending through the apertures of the insulating strip and the adjacent plate, the other insulating strip extending across the aperture in the adjacent 50 plate to form an insulating window therefor.

2. An electric heater having in combination a resistor, a pair of sheet metal plates forming an inclosure for the resistor and having alined oppositely positioned apertures, insulating strips separating the resistor from the plates, one of the strips extending over the aperture in the adjacent plate to form a removable window therefor, and a hollow rivet connected with the resistor and extending through the aperture of

the opposite plate and insulated from both plates.

3. An electric heater having in combination a resistor, a sheet metal armor insulated from and surrounding the resistor and having alined apertures in opposite sides thereof, a hollow terminal rivet connected with the resistor and extending through one of the apertures, and a removable insulating covering for the other aperture. 75

4. An electric heater having in combination a resistor, a sheet metal armor insulated from and surrounding the resistor and having alined apertures in opposite sides thereof, a hollow terminal rivet connected with the resistor and extending through one of the apertures, and a removable insulating covering for the other aperture positioned within the armor. 80

5. An electric heater having in combination a resistor, insulating strips on each side of the resistor, a pair of sheet metal plates forming an inclosure for the insulated resistor and having alined apertures over one of which the adjacent insulating strips extends to form a removable window therefor, and a hollow terminal rivet connected with the resistor and insulated from and extending through the aperture in the other plate. 85

6. An electric heater having in combination a resistor, a sheet metal armor insulated from and surrounding the resistor, said armor being provided with alined apertures on opposite sides thereof, and a hollow terminal rivet insulated from the armor and 95 positioned in one of the apertures in alinement with the other aperture to permit the heater to be mounted against a flat surface with the terminal rivet insulated therefrom or upon a conducting rod in contact with 100 the terminal rivet and extending through the alined apertures. 105

7. An electric heater having in combination a resistor, a casing insulated from and inclosing the resistor and having an aperture 110 in the wall thereof, a removable insulating covering for the aperture, and means for connecting a conductor with the resistor when said insulating covering is removed.

8. An electric heater having in combination a resistor, a casing insulated from and inclosing the resistor and having an aperture in the wall thereof, a terminal positioned opposite the aperture and connected with the resistor, and a removable insulating covering for the aperture. 115

9. An electric heater comprising a casing having an aperture, a resistor within the casing and insulated therefrom, a removable insulating covering for the aperture positioned 120 within the casing, and means for connecting a conductor with the resistor when said insulating covering is removed. 125

10. An electric heater comprising a casing having an aperture, a resistor within the cas- 130

ing and insulated therefrom, a terminal connected with the resistor and positioned opposite the aperture, and a removable insulating covering for the aperture positioned within 5 the casing.

11. An electric heater comprising a casing having an aperture, a resistor within the casing and insulated therefrom, and a remov-

able insulating covering for the aperture, whereby when said insulating covering is 10 removed a conductor may be connected with the resistor.

In witness whereof, I have hereunto subscribed my name.

EDWIN N. LIGHTFOOT.
